*Inventor
Fred J. Keppler.*

UNITED STATES PATENT OFFICE.

FRED J. KEPPLER, OF BUFFALO, NEW YORK.

CONVERTIBLE BUILDING.

Application filed August 25, 1920. Serial No. 405,858.

To all whom it may concern:

Be it known that I, FRED J. KEPPLER, a citizen of the United States, residing in Buffalo, in the county of Erie and State of New York, have invented new and useful Improvements in Convertible Buildings, of which the following is a specification:

This invention relates to a convertible building of the general type shown in my pending applications No. 302,569, filed June 7, 1919, and Nos. 383,418 and 383,419, filed May 22, 1920.

The object of the present invention is to provide improved means for removably mounting posts between the floor and ceiling of a building and also detachably connecting portable walls or partitions with said posts, so that the space within the building may be readily subdivided into compartments of various forms, sizes and numbers as occasion may require.

In the accompanying drawings:

Figure 1 is a horizontal section of my invention taken on the correspondingly numbered line in Fig. 3. Figure 2 is a vertical section taken on line 2—2, in Fig. 1. Figure 3 is a sectional elevation on a reduced scale showing a complete post assembled with the floor and ceiling. Figure 4 is a cross section taken on line 4—4 in Fig. 2. Figure 5 is a fragmentary vertical section of a modified form of the joint between the post and the ceiling or floor. Figure 6 is a horizontal section taken on line 6—6, Fig. 5. Figure 7 is a fragmentary vertical section showing a modified form of the guide plates which receive the catches. Figure 8 is a horizontal section taken on line 8—8, Fig. 7.

Similar characters of reference refer to like parts throughout the several views.

5, 6 represent the horizontal floor and ceiling of a building which may be constructed in any suitable manner so that the floor and ceiling are maintained in position relative to each other and enable the space between the same to be subdivided as desired by means of my invention. The means whereby this space is subdivided consists generally of a plurality of upright junction members, posts, columns or standards 7, couplings 8 and 9 interposed between the ends

of each post and the ceiling and floor and partitions 11 engaging their upper and lower horizontal edges with the ceiling and floor and connected at their vertical edges with 55 the post. Each of the posts 7 is preferably hollow and has its body constructed of wood which latter is square in cross section and made up of four sides, as shown in Fig. 1. The upper and lower ends of each post are 60 reduced and provided with metal caps 80 similar to those described in my pending application No. 383,418, filed May 22, 1920. Between the upper and lower ends of the post are arranged couplings whereby the 65 post is removably secured to the support formed by the ceiling and floor, and the partitions are also supported relatively to the posts.

Each of the ceiling post couplings 8 comprises a hollow cup shaped body square in shape and of the same dimensions as the outside dimension of the post thereby allowing the sides of the coupling and post to be in the same plane when assembled. The 70 inner side or socket 81 of the coupling 8 is also square in shape and of a dimension suitable to take the reduced end of the cap 80, the socket to have enough depth to allow enough clearance between the top of the cap 80 and the bottom of the socket for the purpose of securing a tight fit between the shoulder of the cap and the wall of the coupling. This coupling is fastened to the ceiling by 75 means of screws 82, as shown in Fig. 2.

The floor post coupling 9 comprises a hollow body square in cross section and of the same dimensions as the outside dimension of the post, thereby allowing the sides of the coupling and post to be in the same plane 80 when assembled. The inner side or socket 90 of the coupling 9 is round in shape and threaded to take the externally threaded follower 10. The coupling 9 is provided with a flange 91 for the purpose of securing a good footing and grip on the floor when the follower 10 is tightened up against the lower end of the post, thereby substantially securing the post in position.

Each of the partitions, walls or panels 11 100 is provided at its lower corners with a recess 110 which in the assembled position of the

parts receives the flange 91 on one of the lower coupling bodies so as to form a practically closed joint therewith and effect a complete separation of the compartments or rooms within the building on opposite sides of the partition.

In order to hold the partitions in their upright positions, they are interlocked with each of the posts by means which may be variously constructed but which in the form shown in the drawing are constructed as follows:

15 represents a plurality of arms or rods connected to a centering piece 16 by means of screw joints thereby forming a cross shaped guide. On the outer end of each arm is mounted a retaining ball or spherical catch 13 which is adapted to move horizontally upon the guide or arm 15 through a hole 22 in the ball and normally project with its spherical front side beyond the front side of the post. This catch is held in its outer position by means of a spring 17 one end of which is guided by and secured to the centering piece 16 while its other end is guided by and secured to the guide sleeve 131 within the retaining ball or spherical catch 13. The latter is also provided with an external flange 130 at its rear or inner end which is adapted to engage the inner side of the post and prevent the catch from moving outward too far. 14 represents a plurality of guiding and wearing plates for the purpose of preventing the flange 130 from destroying the wood post.

21 represents a plurality of holes in the sides of the post for the purpose of providing sockets or pockets which receive the retaining balls or spherical catches.

40 In the vertical edges of each partition holes 20 are provided to receive metal sockets 12 which are adapted to receive the front ends of the catches 13 and hold the partitions or walls in place.

45 In the operation of dividing the space between the ceiling and floor into compartments, a coupling body is first placed on the floor in line with each of the coupling bodies which is secured to the ceiling and between which and the respective floor coupling body a post is to be erected. A post is now placed vertically in line with the sockets of a pair of ceiling and floor coupling bodies and then the followers 10 in the

55 sockets thereof are turned by inserting a tool in one opening after another in the side of the follower and moving the tool circumferentially until the opposite end of the post is firmly gripped between the upper socket 8 and the lower follower 10 and securely held in place. A partition is now placed in an upright position and moved laterally so that the catches on the adjacent posts engage with the sockets or seats 12 of the

parts receives the flange 91 on one of the lower coupling bodies so as to form a practically closed joint therewith and effect a complete separation of the compartments or rooms within the building on opposite sides of the partition.

70 prevent disengagement of the catches from these seats by lateral pressure against the partition, means are provided for locking the catches in engagement with the seats which means preferably consist of locking pins 19 pushed into openings in opposite sides of each catch and each passing through a slot 190 formed partly in the face of the socket 12 in which the catch seat is formed and partly in the adjacent portion of the wall. By this means a party occupying a room on one side of a partition cannot unfasten the partition and gain access to the room on the opposite side of the partition, thereby preventing intrusion and ensuring 75 privacy and safety of the occupant of the respective rooms.

80 Instead of reducing the upper end of the post as shown in Figs. 2 and 3, the full diameter of the same may be retained to the end thereof by providing the end of the post with an internal socket 83 which receives a coupling head 84 secured to the ceiling 6. If desired the several wearing plates may be constructed in one piece or band so as to 85 practically form a square lining for the post, as shown at 140 in Figs. 7 and 8, which lining is secured to the sections of the post and holds the same together and is provided with holes 141 in line with corresponding 90 holes 142 in the post for receiving the catches 13.

95 Obviously, one or more partitions may be 100 associated with each post and the respective catches depending upon the manner which it is desired to divide the space. Inasmuch as the catches are all alike in construction and operation, the same are capable of universal use regardless of whether only one or a plurality of partitions are associated with the same and the respective post.

105 Furthermore, this construction is very simple and easily operable which renders it easy to either put up the partitions or take them down, as desired.

110 Moreover, this construction permits of readily opening up the entire space between the ceiling and floor when the same is desired for dancing or other purposes, and it also permits this space to be quickly subdivided into separate rooms thus rendering the same particularly suitable for camping or outdoor life, also for housing purposes of every description.

115 I claim as my invention:

120 1. A convertible building having a support, a partition, and means for detachably connecting said partition and support comprising a hollow post, catches mounted on the post and engaging with said partition, means for guiding said catches comprising a center piece arranged within the post and provided with a plurality of arms on each of which one of said catches is adapted to slide 125 and means on the partition for receiving 130

said catch and connecting said post and partition.

2. A convertible building having a support, a partition, and means for detachably connecting said partition and support comprising a hollow post, catches mounted on the post and engaging with said partition,

means for guiding said catches comprising a center piece arranged within the post and provided with a plurality of arms on each of which one of said catches is adapted to slide, and a spring interposed between each of the catches and said center piece. 10

FRED J. KEPPLER.
